United States Patent

Des. 240,612
Patented July 20, 1976

240,612

WEIGHT

Harry C. Becker, 190 Broadview Ave.,
New Rochelle, N.Y. 10804

Filed Jan. 8, 1975, Ser. No. 539,540

Term of patent 14 years

Int. Cl. D10—07

U.S. Cl. D10—94

The figure is a typical top perspective view of a weight showing my new design; the bottom being flat, plain and unornamented.

I claim:

The ornamental design for a weight, as shown and described.
